METHOD OF CUTTING FUR OR THE LIKE

Alvin L. Diller, Lexington, and Charles A. Cameron, Malden, Mass., assignors to The B. F. Goodrich Company, New York, N. Y., a corporation of New York

Application December 3, 1942, Serial No. 467,786

3 Claims. (Cl. 164—17)

This invention relates to a method and device for cutting fur and the like and is especially useful for cutting patterned elements from a fur pelt for use in lining articles of footwear and for similar purposes.

Many articles of footwear, such as the aviator's boot shown in Fig. 5, are lined with sheep skin or fur to provide warmth and comfort. Such linings customarily are provided by cutting several patterned elements from the fur pelt and then securing these elements in the footwear structure with their contiguous edges substantially in abutting relation. It is highly desirable that the seams or joints between the abutting fur elements should not be apparent to an observer. Because of this requirement, it has been necessary heretofore to cut out the lining elements by hand, since conventional machine-cutting methods, as with a conventional knife-edged die, serve to cut the hair as well as the leather of the fur so that a considerable quantity of the fur hair was removed along the cut edge. When two pieces of fur cut in this manner are joined in abutting relation a distinct V-shaped channel is apparent in the fur along the seam.

The present invention provides for machine cutting of fur elements without substantially cutting the hair so that two of the resulting elements may be abutted together to produce a seam which is entirely invisible when viewed from the hair side of the fur. This is accomplished by utilizing a die or other cutting member having a serrated fur-engaging edge. The serrations are so arranged and proportioned that the leather is merely perforated along a line without completely severing the leather or cutting any substantial amount of the hair. Then, the leather is torn along the line of perforation to complete the severance. The entire outline of the desired element may be cut in this manner or, as is frequently desirable, a portion may be cut in the manner described, while another portion of the outline is simultaneously cut with a conventional knife edge effecting complete severance of the leather and also cutting of the hair. Such combination of the two types of cutting is useful for example in cutting quarter lining elements of fur for a boot. In such lining elements the top edge ordinarily is covered with a binding so that cutting of the hair is not objectionable, but in fact desirable, while a side edge extending down the back of the boot will abut a similar quarter lining element so that cutting the hair along this line is highly undesirable in the interest of providing an invisible seam.

The invention will now be described in greater detail with reference to the accompanying drawing of which:

Fig. 1 is a perspective view of a cutting die embodying our invention, the die being one designed for cutting quarter lining elements for an aviator's boot;

Fig. 2 is a vertical cross section taken along line 2—2 of Fig. 1.

Fig. 3 is an elevational view of a conventional clicking press with a fur pelt in place on the press table and the die of Fig. 1 in place on the pelt ready for cutting;

Fig. 4 is a perspective view of the pelt after the cutting operation and showing the step of tearing the leather along the line of perforation.

Fig. 5 is a perspective view of an article of footwear such as an aviator's boot lined with sheep skin elements cut in accordance with the invention, the hair having been "cut away" in the region of the seam.

Fig. 6 is a view showing in cross section the joint between two fur elements cut in accordance with the invention.

Fig. 7 is a perspective view of a modified form of die structure also embodying the invention.

A cutting die 10 designed for cutting quarter lining elements for aviator's boots and typically embodying our invention is illustrated in Figs. 1 and 2. The die 10 conveniently may comprise a strip of spring steel 11 bent in accordance with the trapezoidal outline of the desired quarter lining element. For support, the strip 11 may be bolted to a wooden frame 12 in accordance with usual die-making practice. One of the projecting edges of the strip 11, such as the edge 13, is provided with a sharp knife edge. The other three projecting edges, 14, 15, and 16 are however, provided with serrations 17, 18, the serrations being so arranged that only the serrations pierce the leather of the fur during the cutting operation. Thus, the serrations are sharply pointed, while the intervening crotches are intentionally left dull and incapable of cutting the leather or hair. Also, the individual serrations preferably are substantially greater in length than the distance between adjacent serrations. It will be appreciated that serrations so arranged will produce a closely perforated line capable of being readily torn in much the same manner that ordinary perforated paper is torn.

To cut a quarter lining element from a sheep skin or other pelt 18, the pelt is placed on the table 19 of a conventional clicking press 20 with

the hair side of the pelt toward the top of the table, that is, with the leather side exposed. The cutting die 10 is then placed in position with the cutting edges in contact with the exposed leather of the fur. The clicking press arm 21 is then swung into position over the die and the press is operated, in the customary manner, to force the die into the pelt.

During the cutting operation, the serrated edges of the die pierce the leather but do not cut the hair and consequently form lines of perforation as shown more clearly in Fig. 4. At the same time, the knife edge 13 of the die severs the fur completely, cutting both the leather and the hair along this edge. The numerals 13c, 14c, 15c, and 16c indicate the margins of the fur cut by the die cutting edges bearing corresponding numerals. The fur is then grasped along the completely severed edge 13c and the leather is torn by pulling along the perforated lines as illustrated in Fig. 4 to produce the lining element 22.

The lining element 22 is then embodied in an aviator's boot 23 shown in Fig. 5, the knife-cut margin 13c of the element extending along the top edge of the boot while the serration-cut margin 16c extends down the back of the boot where it abuts with a similarly cut margin of a second quarter lining element 22a. As shown in the drawing the seam between the elements 22 and 22a is entirely invisible to an observer.

The invisible character of a seam between two pieces of fur which have been serration cut in accordance with the invention is perhaps more clearly shown in the cross-sectional view of Fig. 6.

The principles of the present invention are adaptable to various types of die structures. For example, the invention may be embodied in the modified form of die shown in Fig. 7. This die comprises a ring-like structure 25 made of tool steel or other suitable material and having a sharp knife edge along three sides, 26, 27, and 28 of the die while the fourth side 29 is provided with serrations of the character previously described. The back edges of the die member are generally flat for engagement with the clicking press arm.

The present invention has facilitated greatly the cutting of fur lining elements for footwear. Machine-cutting operations have been substituted for the hand-cutting operations previously considered necessary. As a result, substantial sav-

ings in time, labor, and expense have been realized. Also, material improvements in quality of the products have been achieved through more efficient and uniform cutting of the fur elements.

5 Although the invention has been described in considerable detail with particular reference to the cutting of patterned lining elements from sheep skin for use in footwear, it will be understood that the invention is by no means limited to such use and that it may be employed in cutting furs of any type and for a wide variety of uses. Consequently, it will be understood that the terms fur, hair, and leather have been used in their broader sense to include various types of fur whether the hair be woolly or more filamentary in character. Similarly numerous modifications and variations in details of the structures and procedures hereinabove described may be effected without departing from the spirit and 10 scope of the invention as defined by the appended claims.

15 We claim:

1. The method of cutting fur or the like which comprises closely perforating the leather of the fur along a line without substantially cutting the hair, and then tearing the leather along the line of perforations.

2. The method of cutting a patterned element of fur or the like from a pelt or similar sheet, which comprises closely perforating the leather of the fur along a portion only of the outline of the desired element without substantially cutting the hair along said portion, simultaneously severing completely the leather along another portion 20 of the outline of the desired element, and then tearing the leather along the aforesaid line of perforation.

3. The method of cutting from a pelt or the like a patterned element of fur such as a lining element for an article of footwear in which an edge portion of the said element will abut an edge portion of another fur element, said method comprising closely perforating the leather of the fur along the abutting edge portion without 25 substantially cutting the hair along said portion, simultaneously severing completely the leather along another edge portion of the element, the aforesaid perforating and severing being performed in a single die-cutting operation, and 30 then tearing the leather along the aforesaid line of perforation.
